CLAIM

An ornamental design for an illuminated tray, as shown and described.

DESCRIPTION

FIG. 1 is a perspective view of an illuminated tray embodying my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

Throughout the drawings the broken lines depict portions of the illuminated tray that form no part of the claimed design.
